UNITED STATES PATENT OFFICE.

EDWARD H. BENJAMIN, OF OAKLAND, CALIFORNIA.

AIR-PURIFIER FOR CARBURETEES.

1,095,695.

Specification of Letters Patent.

Patented May 5, 1914.

Application filed April 2, 1913. Serial No. 758,327.

To all whom it may concern:

Be it known that I, EDWARD H. BENJAMIN, a citizen of the United States, residing at Oakland, in the county of Alameda and State of California, have invented new and useful Improvements in Air-Purifiers for Carbureters, of which the following is a specification.

This invention relates to a device for 10 cleansing the air which is introduced into carbureters, in the use of internal combustion engines for pleasure vehicles, and particularly for road work, harvesting, etc. The carbureters rapidly become clogged by 15 reason of the dirt which is constantly drawn in filling the carbureter up, and additionally a good deal of the air carries fine dust into the cylinders which scores and wears them so that they need boring out and new pis- 20 ton rings.

The invention consists of the parts and the construction and combination of parts as hereinafter more fully described and claimed, having reference to the accompany- 25 ing drawings, in which—

Figure 1 is an outside view of the casing. Fig. 2 is a vertical section of the device. Fig. 3 is a plan view of the apparatus.

In the present device, the outer casing A 30 is made with peripheral openings, as at 2, which may be five or six in number. Within this casing is fitted a perforated or screened basket 3 and inside of this is another similar one 4. The outer chamber A 35 is supplied with water from a sealed source by gravity through a pipe, as shown at 5. The end of this pipe dipping into the water in the chamber A will maintain the supply and whenever the water falls below that 40 level, air will be admitted through the pipe 5 to the closed supply chamber and allow a little more water to come in and maintain the level. The space below and around the chamber 4 and between it and the exterior 45 chamber 3 is filled with sponge or other porous material through which air will freely draw, which sponge dipping into the water will by capillary attraction absorb enough to keep it partially full of water. 50 The dust laden air drawn in through the openings in the outer casing A and through the passages in the part 3 will also pass through the sponge or similar material and will thus arrest the dust and prevent it from 55 going into the carbureter. The air thus cleansed will be drawn through this appara-

tus and the opening 6 to the carbureter with which it is connected, by the reciprocation of the engine pistons.

The casing A has a flange 7 at the top, 60 corresponding with a similar flange of the fixed head portion, through which the air ultimately passes to the carbureter; a bolt 8 connects these flanges in such manner that the casing A may swing around the bolt in a 65 horizontal plane and expose its open upper side and the interior baskets and spongy filling which can thus be easily removed, cleaned and replaced without disturbing any fixed part of the apparatus. On the side 70 opposite to the hinge bolts 8 is a stop and locking device, as at 9, which serves to retain the parts in proper operative relation when closed.

Having thus described my invention, what 75 I claim and desire to secure by Letters Patent is:

1. In an apparatus of the character described, a casing having air inlet openings in its sides and a closed bottom, an inlet for 80 water, annular interior flanges of less diameter than the interior of the casing, a perforated screen chamber supported by the flanges, a second smaller concentric screen chamber located within the first named 85 chamber, and an intermediate porous spongy filling, the lower part of which dips into the water, the upper part of the casing having an air discharge opening.

2. A carbureter filter comprising concentric foraminous baskets with supporting flanges at the top and an interposed spongy absorbent filling, a casing with inwardly projecting flanges by which the baskets are supported out of contact with each other 95 and with the casing, said casing having a discharge opening at the top and air inlet openings around the sides, and a water supply for the spongy filling.

3. In an air purifier for carbureters, a 100 casing having peripheral openings and a closed bottom, means to supply water to the casing interior to allow same to contact with the bottom, a foraminous basket in the casing having its bottom contacting with the water in the casing, a second foraminous basket arranged within the first named basket in spaced relation to the latter, means to support said baskets in their relative positions within the casing, a mass of absorbent 105 material in the space between the baskets, and means to close the casing top having an

outlet which communicates with the open ends of the baskets.

4: In an air purifier for carbureters, a casing having a closed bottom and formed with peripheral openings located above the bottom, means to supply water to the casing interior, a foraminous hollow member having a closed bottom and an open top mounted in the casing and being in connection with the water, said member having its sides extending over the peripheral openings of the casing, a lining of absorbent material

for said member, means to hold the lining in place, and a closure for the casing disposed over the open top of the hollow member and having an outlet which communicates with the open top of said member. 15

In testimony whereof I have hereunto set my hand in the presence of two subscribing witnesses.

EDWARD H. BENJAMIN.
